CALCULATING MACHINE

Hansguenter Tilch, Rothenbach (Pegnitz), Germany,
assignor to Diehl, Nuremberg, Germany

Filed Aug. 8, 1966, Ser. No. 3,392

Claims priority, application Germany Feb. 9, 1966

Term of patent 14 years

(Cl. D64—11)

FIG. 1.

FIG. 2.

FIG. 3.

FIG. 4

FIG. 1 is a perspective view of a calculating machine showing the new design;

FIG. 2 is an elevational view of the side opposite to that seen in FIG. 1;

FIG. 3 is a bottom plan view; and

FIG. 4 is a rear elevational view thereof.

I claim:

The ornamental design for a calculating machine, as shown.
